UNITED STATES PATENT OFFICE

2,068,692

DEVICE FOR TREATING STUPES AND
THE LIKEWilliam P. Myron, San Francisco, Calif., assignor
to F. A. Hamilton, San Francisco, Calif.

Application August 11, 1933, Serial No. 684,666

7 Claims. (Cl. 21—18)

This invention relates to a method of treating stupes and the like, and a device for the same.

The most common method of preparing a stope or compress consists in dipping cloth or tow, or 5
pledget of lint, or the like in warm water and then wringing it to a desired moisture content. Heretofore the only improvement in the above mentioned primitive method was to provide a receptacle or box filled with boiling water and 10
to place the cloth into the water, and then of course to wring the cloth to obtain the desired degree of dampness. These old methods and the devices used in connection with the old methods had many disadvantages; outstanding 15
among these disadvantages are two, namely the lack of sterilization and the loss of heat, both primarily due to the wringing operation which necessarily reduces the temperature of the stope and also in the course of manipulating it with 20
hand, or with the wringer, whatever sterilizing effect the boiling water might have had on the cloth is destroyed.

The primary object of this invention is to eliminate the disadvantages of the old methods, 25
and to prepare a stope by subjecting cloth or the like to the action of steam at a sterilizing temperature, and in the absence of air, for a definite time to obtain the desired dampness, thereby obviating the use of boiling water and 30
of wringing.

Another object of the invention is to provide a device whereby cloth or the like can be heated, sterilized and moistened to a definite degree of dampness in one easy operation without any 35
danger of scalding the operator, means being provided in the device to form a tight, sealed inclosure, in which the cloth is supported in spaced relation to suitable steam inlets and outlets so as to be penetrated by steam, which has a higher 40
temperature than boiling water; control means being provided to exhaust the air from the inclosure and from the cloth, and then to produce a flow of steam whereby a stope of the usual size is heated and dampened in a relatively short time. 45
For instance a stope or compress of the maximum desired dampness can be obtained in my device in about two minutes. Stupes of lesser dampness, but fully sterilized, can be obtained by proportionally shorter periods of treatment in the 50
inclosure.

A further object of the invention is to provide a so-called "stope box", wherein a stope is produced by steam treatment, safety devices being provided on the box to prevent escape of steam, 55
and scalding of the operator.

A still further object of the invention is to provide a device of the character described which is adapted to heat and sterilize stupes as well, as adapted to sterilize any instruments or surgical appliances.

In this specification and the annexed drawing the invention is illustrated in the forms, which are at present preferred, since the same have been found in practice to give satisfactory and reliable results, but it is to be understood that the invention is not limited to such form, because it may be embodied in other forms; and it is also to be understood that in and by the claims following the description, it is desired to cover the invention in whatsoever form it may be embodied.

The invention is clearly illustrated in the accompanying drawing, wherein

Figure 1 is a front view of my device showing the box partly in section and showing part of the inlet conduits.

Figure 2 is a plan view of my device, the cover being shown partly broken away to expose to view a portion of the tray and of the baffle.

Figure 3 is a cross sectional view of my device the section being taken substantially on the line 3—3 of Fig. 1.

Figure 4 is a diagrammatic side view of the box and cover, and the means for lifting the cover, the opened cover being indicated in broken lines.

Figure 5 is a fragmental sectional view of my device showing its arrangement for use with high pressure steam.

Figure 6 is a sectional plan view of one of the quick acting valves and its connection to the actuating rod.

Figure 7 is a fragmental view of the pivot pin connecting the actuating rod to the valve operating arm, the pin being shown in elevation.

The method of preparing a stope includes the placing preferably of folded cloth, or the like, into an inclosure, the exhausting of the air from the inclosure and the replacing of the air by a flow of steam through the inclosure. The flow of steam is so directed that it impinges on the cloth, and penetrates into the interstices of the cloth. The cloth is left in the inclosure for about two minutes, or less, the time being predetermined and in direct proportion with the required dampness of the stope.

In carrying out my invention with respect to my device, I make use of a steam box, or receptacle 6, which has a bottom 7, a front 8, a rear-wall 9, and sides 10 and 11. The top of the box is open, and it has an enlarged flange 12 all

around the edges thereof, in which is formed a groove 13, extended, all around in the flange 12 to retain a packing 14 therein. The box 6 is preferably supported on a pair of spaced wall brackets 16, which are secured to the wall in any suitable manner.

In the bottom 7 of the box 6 are a steam inlet 17, a steam outlet 18, and a vacuum break passage 19, arranged in a line on the transverse center line of the bottom 7.

The box 6 can be covered by a cover 20, which is dished at 21, and reinforced by ribs 22'. The cover 20 is so disposed that the concave side of its dished portion 21 forms the inside of the cover. A pair of hinge-lugs 22 extend from the rear edge of the cover 20, so that the end portions of the lugs 22 extend downwardly and in parallel spaced relation to the outside of the rear wall 9. From the rear wall 9 extend bosses 23. Each boss 23 has bearings 24 therein, and a pin 26 is extended through each bearing 24 and the lug 22 at said bearing 24 to pivotally connect the cover 20 in place. Each pin 26 has a head on one end, and a cotter pin 27 in the other end thereof to retain the pin 26 in place. Each boss 23 has an abutment shoulder 28 formed thereon, and the hinge lugs 22 on the cover 20 are so formed as to abut against and rest upon the respective shoulders 28 when the cover 20 is open, thereby to limit the rearward swing of the cover 20.

On one side of the cover 20 is an extension 29 which protrudes beyond the plane of the side 11 of the box 6. A link 30 is pivoted at one end to the extension 29, extends alongside the side 11 and is bent at its other end forwardly substantially at right angles and is pivoted to the end of a handle bar 31. The handle bar 31 is fulcrumed intermediate its ends at 32 on the side 11 of the box 6. The fulcrum 32 being so located and the length of the link 30 and bar 31 are such that the handle bar 31 extends upwardly and forwardly alongside the side 11 when the cover 20 is closed. By moving the forward end 45 of the handle bar 31 downwardly the link 30 is pushed upwardly so as to turn the cover 20 to open position. When the cover 20 is fully opened the bent end of the link 30 is above the imaginary line between the extension 29 and the fulcrum 50 32 so as to prevent the closing of the cover 20 unless the handle bar 31 is turned.

The cover has a flange 33 extended from its inside face for engagement with the packing 14 in the flange 12 of the box 6. In order to seal the box 6, the cover is positively pressed in place. Ears 34 extend from a boss on the front edge of the cover 20, over the outside of the front 8. An engagement member, in the form of a roller 36 is mounted on a pin 37 between the ears 34 so that the axis of the roller 36 is at right angles to the plane of the front 8, and the roller 36 is spaced from the top of the saddle formed by the connected ears 34, thus forming a keeper wherein the bolt 38 of an eccentric latch 39 can be pressed. The latch 39 is pivoted at 40' on the front 8, and its handle portion is heavier than its bolt and is on one side from said pivot 40', so that the latch 39 swings to disengage position by its own weight whenever it is released from the keeper. The bolt 38 is arcuate and is adapted to engage the top side of the roller 36 as the latch 39 is turned in clockwise direction, viewing Figure 1.

It is to be noted that the packing 14 is resiliently compressible and the pressure exerted

by the latch bolt 38 on the roller 36 presses the flange 33 into the packing 14, thereby it accomplishes a tight seal all around the top of the box 6 and also tightly holds the cover 20 in closed position. To disengage the latch bolt 38 the latch 39 is turned in contra-clockwise direction viewing Figure 1, and it remains in disengaged position by reason of its own weight. As the packing 14 wears, the roller 36 can be replaced by a roller of larger diameter to compensate for the wear, assuring a tight seal as long as the packing 14 lasts.

On the edge of the dished portion of the cover 20, nearest to the rear wall 9 of the box 6 is a longitudinal trough 40 opened toward the dished portion of the cover 20 so as to cooperate therewith for collecting condensation therein. When the cover 20 is opened the trough 40 is opened upwardly. When the cover 20 is closed the trough 40 is opened in a half inverted position 20 in the direction of the front 8 so as to return the condensed moisture into the box 6 adjacent the inside face of the rear wall 9.

The inside of the box 6 is arranged as follows: A perforated tray 41, preferably made of screen is supported on lugs 42 in spaced relation above the bottom 7. There are a plurality of such lugs 42 extended from the front 8, rear wall 9, and sides 10 and 11 inwardly of the box 6. A stope 43 is placed on the top of the tray 30 41. A baffle 44 is suitably fixed into the box 6 along the entire length of the inside of the front 8. The baffle 44 is bent at a longitudinal edge thereof downwardly to the bottom 7. The baffle 44 extends over the intake 17 so as to form an intake chamber 46. The top of the baffle 44 is perforated at 47, while the bent side thereof is scalloped at 48 adjacent the bottom 7. The portion 48' of the baffle immediately adjacent and above the intake 17 has no perforations on it, 40 hence the steam does not escape upwardly immediately as it enters the box 6 but it is distributed laterally in the intake chamber 46 before it rises in the box.

The outlet 18 is suitably connected to the usual suction device of the steam-circulation system, diagrammatically indicated, for the purpose of illustration, by a pump 49, in Figure 3. The outlet 18 in the bottom 7 is covered by a perforated disc 50 with scalloped sides, suitably secured to the bottom 7.

In order to prevent injury by excessive pressure or vacuum, a pressure safety valve 51, and a vacuum safety valve 51' are provided on the rear wall 9 of the box 6. The safety valves 51 and 51' 55 are of the usual construction and are adapted to open respectively in the event of excessive pressure or vacuum in the box 6.

The vacuum break opening 19 is connected to atmosphere, as shown in Figure 2, when the device 60 is used with low pressure steam, from two pounds to eight or nine pounds. But it is plugged when high pressure steam of about ten pounds or higher is used, as hereinafter described.

On the device shown in Figures 1 and 3, the flow through the inlet 17, the outlet 18 and the vacuum break 19 is controlled by suitable quick operating valves 52, 53, and 54 respectively. For instance usual quick closing gate valves can be employed, which include a hollow casing 56, in which the passage 57 is controlled by a gate valve 58, which latter is moved sidewise into and out of the passage 57 by lever 55 and a pin 59. An arm 60 has polygonal holes 61 in each end thereof. One of the holes 61 is engaged with a correspond-

ingly polygonal end of the pin 59, the other hole 61 with a portion of a pivot pin 62, also of polygonal cross section. The pins 62 are pivotally secured in an actuating rod 63, which latter is 5 slidably guided in a bracket 64 extended downwardly from the box 6. The rod 63 terminates at its forward end in a handle in front of and below the box 6.

It is to be noted that the gate valve 54 operates 10 in opposite direction to the gate valves 52 and 53 so that when the valves 52 and 53 are opened, the valve 54 is closed, and vice versa. Hence by 15 pulling the rod 63 forwardly of the box 6, the inlet and outlet valves 52 and 53 are closed, and the vacuum break valve 54 is opened. In case of low pressure steam the inlet valve 52 is connected to the usual steam piping, the outlet valve 53 is connected to the suction pump 49, and the vacuum break valve 54 is connected to the atmosphere. 20 A suitable main steam valve 66 controls the steam flow toward the inlet valve 52.

In order to provide complete safeguard against scalding a spring 45 is connected to the rear end 25 of the rod 63 and is so arranged as to normally urge the same toward intake closing position. The rod 63 has on its underside a notch 55' which is so arranged that it is aligned with a catch 55' of a tripping rod 65 when the rod 63 is pulled forwardly far enough to open the intake valve 52. The tripping rod 65 is held in brackets 30 on the forward wall of the box 6 and is urged upwardly by a spring 65' between a collar 65'' fixed on the tripping rod 65 and the upper face, of one 35 of its guide brackets. The upper end of the tripping rod 65 is enlarged into a head and extends in the path of the latch 39, so that when the latch 39 is turned in contra-clockwise direction, viewing Figure 1, it trips the rod 65, and releases the catch 55' from the rod 63, thereby permitting 40 the automatic closing of the intake valve 52 by the action of the spring 45 even before the latch bolt 38 is completely disengaged from the roller 36. Consequently the cover 20 can not open without automatically shutting off the steam from the 45 interior of the box 6.

The embodiment shown in Figure 5 is the device in use with high pressure steam. The device in its general organization is the same as heretofore described, but the steam passage and flow is 50 different. A vent hole 67 in the rear wall 9 of the box 6 above the position of the tray 41 and stufe 43, is shown plugged in Figure 2, in case of low pressure steam. However in the event high pressure steam is used the vent 67 is connected to a 55 vent conduit and functions as a steam outlet. A suitable thermostatic trap 68, of the usual design is connected to the outlet valve 53 to collect condensation. The vacuum break 19 is plugged, or its valve 54 disconnected from the rod 63 so as to 60 remain closed at all times. A suitable reducing valve 69 is connected in series with the intake valve 52, to reduce the steam pressure to about ten pounds or slightly higher.

A back pressure device is connected to the vent 65 67 and it consists of a suitable pipe coupling 70, across the passage 71 of which is fixedly held a disc 72 with a small orifice 73 in its center whereby a back pressure is created in the box with the attendant increase of temperature in the box.

In operation the stufe 43 is placed on the tray 41. Then the cover 20 is closed by moving the free end of the handle 31 upwardly, and the cover 20 is drawn tight by turning the latch 39 in a clockwise direction viewing Figure 1. Then 70 75 the main valve 66 is opened. The rod 63 is pulled

forwardly, whereupon, the inlet and outlet valves 52 and 53 are opened. The air in the box at this time is practically cold, and the imperforate portion of the baffle 44 directs the steam sidewise instead of directly into the box, hence the suction 5 through the outlet creates almost instant vacuum in the box 6. As the steam flowing through the inlet 17 fills the box and flows to the outlet its heat reduces the vacuum and allows slower flow and expansion of the steam in the box. Due to 10 the fact that both the inlet 17 and the outlet 18 are on the bottom, below the stufe 43, the condensation and heavier moist vapor remains closer to the bottom 7, and the hotter and dryer steam rises toward the top into and through the interstices of the stufe 43. Thus the dampness of the stufe depends definitely on the length of time it is treated. In the beginning the stufe is primarily heated and slightly dampened, but the dampness increases in direct proportion with the 20 period of time during which the stufe 43 is subjected to the action of the steam.

During all this operation the vacuum break valve 54 remains closed. After the stufe has been in the box 6 for a predetermined time, the 25 rod 63 is pushed rearwardly, thereby it closes the steam inlet and outlet valves 52 and 53 and opens the vacuum break valve 54. The steam remaining in the box 6 immediately escapes through the open valve 54. Then the cover 20 30 is opened, and the stufe 43 can be removed, ready for use, without any further handling or wringing.

In the event of the higher steam pressure device shown in Figure 5, after the closing of the 35 cover 20, and after the rod 63 is pulled forwardly, the steam passes through the reducing valve 69 and through the inlet valve 52 into the steam chest 46, and into the box 6, then it is forced through the stufe 43 and out through the vent 40 orifice 73. The condensed steam escapes through the outlet valve 53 and the trap 68. After the required time the rod 63 is pushed rearwardly closing the inlet valve 52, and the steam remaining in the box 6 escapes through the vent orifice 45 73. Thereupon the cover 20 can be safely raised and the sterilized stufe 43, of the desired temperature and dampness can be removed and used without further handling.

Condensed moisture collects at the bottom 7 50 and is effectively drained, in all the embodiments, through the open sides of the outlet cover 50 and through the outlet 18.

Having thus described my invention what I 55 claim and desire to secure by Letters Patent is:

1. In a device of the character described the combination with a box having an inlet for a heating medium and a cover opposite to the inlet adapted to be opened and closed at will, of a protective shield above a portion only of the 60 bottom of the box around said inlet and being adapted to prevent direct rising of the heating medium opposite said inlet toward the cover so as to evenly discharge said heating medium over the lower portion of the box. 65

2. In a device of the character described, the combination with a box having an inlet for a heating medium, a valve mechanism to control the passage of said heating medium, and a cover on the box; of releasable means to fasten the 70 cover in closed position, means to hold the valve mechanism open, and means actuated by the said fastening means as the latter are released to cause the closing of said valve mechanism.

3. In a device of the character described, the 75

- combination with a box having an inlet for a heating medium, a valve mechanism to control the passage of said heating medium, and a cover on the box; of a coacting latch and a keeper adapted to fasten the cover in closed position on the box, means to hold the valve mechanism in open position; and a mechanism adapted to be acted upon by the latch as the latch is unfastened so as to cause the closing of the valve mechanism.
4. In a device of the character described, the combination with a box having an inlet for a heating medium, a valve mechanism to control the passage of said heating medium, and a cover on the box; of a coacting latch and keeper adapted to fasten the cover in closed position on the box, means to normally urge the valve mechanism to valve closing position, releasable means to arrest the action of said urging means, and means coacting with the latch as the latch is unfastened to release said arresting means and free the action of said urging means to close the valve.
5. In a device of the character described, the combination with a box having an inlet for a heating medium and a valve mechanism to control the flow of said medium, and a cover on the box; of a swingable latch on the box, a keeper on the cover to be engaged by the latch to fasten the cover in closed position, an actuating element whereby the valve is operated, resilient means to urge said element to cause the closing of the valve, a tripping member to hold the actuating member in valve opening position being adapted to be tripped by said latch as the latter is disengaged from said keeper so as to allow the closing of the valve.

6. In a device of the character described, the combination with a box having an inlet and an outlet for a heating medium, a valve mechanism to control said inlet and outlet, and a cover on the box; of means to fasten the cover in closed position on the box, an actuating element to simultaneously operate the valve mechanism to open the inlet and close the outlet, means to move said element to cause the closing of the inlet and the opening of the outlet, a tripping element to arrest the action of said moving means so as to keep the inlet open and the outlet closed; said tripping element being so related to the fastening means that the tripping element is tripped as the fastening means are released thereby causing the said moving means to automatically close the inlet and open said outlet.

7. In a device of the character described, the combination with a box, a cover adapted to seal the box when the cover is closed, a steam inlet and a steam outlet, suction means connected to said outlet, means to break the vacuum in the box, of means to control the inlet, the outlet and the vacuum breaking means so as to simultaneously open the inlet and the outlet and close the vacuum breaking means, means to fasten the cover into closed position on the box, means to hold said control means in inlet opening position, and a tripping mechanism actuated by the fastening means as the latter are unfastened to release said holding means so as to cause the closing of the inlet and the outlet and the opening of the vacuum breaking means.

WILLIAM P. MYRON.
